Specification for Design.

Patented Mar. 25, 1913.

Application filed December 7, 1912. Serial No. 735,529. Term of patent 3½ years.

To all whom it may concern:

Be it known that I, CHARLES A. FAISSOLE, a subject of the King of Italy, residing in the city of New York, borough of Manhattan, in the county and State of New York, have invented a new and original Design for Serving-Tables, of which the following is a specification, reference being had to the accompanying drawing, forming part thereof.

The figure is a perspective view of the serving table, showing my new design.

I claim:

The ornamental design for a serving table, as shown:

CHARLES A. FAISSOLE.
